Wilhelm Jasper
By his Attorney John C. Seifert.

UNITED STATES PATENT OFFICE.

WILHELM JASPER, OF NEW YORK, N. Y.

STRAW-HAT-SEWING MACHINE.

1,034,459.

Specification of Letters Patent. Patented Aug. 6, 1912.

Application filed October 10, 1911. Serial No. 653,933.

To all whom it may concern:

Be it known that I, WILHELM JASPER, a citizen of the United States, residing in the borough of Manhattan, in the city, county, 5 and State of New York, have invented new and useful Improvements in Straw-Hat-Sewing Machines, of which the following is a specification.

This invention relates to straw hat sewing 10 machines, and particularly to a combined presser-foot and gage to facilitate sewing together the straw braid from which straw hats are constructed, although it is also applicable to sewing cords, braids and other 15 trimmings to hats of either straw or felt.

It is the object of the invention to provide an improved sewing machine attachment of this character, which is cheap in construction and efficient in operation, 20 whereby the stitching will always be in a straight line near the marginal edges of the hat and succeeding row of braid, with such edges maintained in firm engagement and a tight stitch assured.

25 In the drawing accompanying and forming a part of this specification, Figure 1 is a perspective view of a Willcox & Gibbs sewing machine with my improved attachment applied thereto. Fig. 2 is a perspective view of my improved attachment. Fig. 3 is a side elevation of the presser foot. Fig. 4 is a perspective view of the gage member; and Fig. 5 is a perspective view of the adjusting screw.

35 Similar characters of reference designate like parts throughout the different views of the drawing.

In the embodiment of my invention illustrated in the drawing, I have shown the 40 same applied to a sewing machine of the Willcox & Gibbs type to be used in connection with a gage 6 adjustably connected to the table 7 by a screw 8 passing through a slot in the gage, said screw also securing a 45 guide rod 9 having a hooked end passing through and extending beyond the guide flange of the gage 6, below which guide rod the braid passes. The gage 6 is adjusted by a rotatable stud 10 having a knurled 50 head and upon which stud is mounted a pinion 11 to mesh with rack teeth 12 on the gage 6.

The presser foot comprises a shank portion 13 having a flange 14 provided with a 55 slot 15 in which engages the shouldered and screw threaded end of the presser-foot bar

16 to which it is secured by a nut 17. The presser bar is of the usual construction provided with the usual means to raise and lower the same and limit the downward movement, a spring yieldingly maintaining it in its lower position. The foot proper 18 is curved upwardly at the forward end and pivotally connected to the shank 13 at the rear end, as shown at 19, by providing 60 the foot with a projection to engage in a slot in a rearwardly extending portion of the shank and passing a pivot pin through such portions of the shank and foot. By this construction, the foot is permitted to 65 have an up and down oscillatory movement parallel with the presser bar. Furthermore, it will be noted that as thus constructed the rear portion of the foot will always be in substantially the same plane, 70 even when it is moved to the dotted line position shown in Fig. 3, the rear portion not being forced down when the forward end moves up, thereby clamping the article being sewed between the stitch plate and 75 foot interfering with the proper feeding thereof by the feeding mechanism. The forward end of the foot is normally forced downward and maintained away from the shank by a spring 20 one end of which engages in a recess or socket in the bottom 80 of the shank and the other end bearing against the top of the foot. A guide pin 21 connected to the foot slidably engages in an aperture or recess in the shank; said 85 pin preventing any sidewise canting movement of the foot.

A gage (designated in a general way by G) to guide the edge of the hat being sewed, and regulating the position of the stitching 90 relative to the edge of the hat, is connected to the shank of the presser foot to have adjustment toward and from the stitch line or needle position, said gage having a guide portion 22 extending beyond the forward 95 end of the foot with a laterally projecting lip 23 curved reversely to the curvature of the foot. The gage is supported by the foot by a pair of pins 24, 24 fixed thereto slidably engaging in holes or apertures 25, 25 in the shank 13, and is adjusted and maintained in its adjusted positions by a set screw 26 having screw threaded engagement with the shank and provided with a knurled head 100 to facilitate the screwing thereof into and 105 out of the shank. The screw engages in a slot formed in the gage by the body of the 110

gage and an upwardly projecting hook shaped portion 28, which portion also carries one of the pins 24, and is provided with a pair of annular shoulders 29, 30 to form 5 an annular groove or recess in which the body and projecting portion 28 of the gage engages, and as the screw is screwed into and out of the shank it carries the gage with it.

10. In the operation of sewing braid together to form a straw hat, let it be assumed that a portion of a hat has been formed, as shown at *a*, (Fig. 1,) and additional braid is to be sewed thereto to finish the hat, the said 15 braid being indicated at *b*. The outer edge of the portion of the hat is run up against the side of the gage G passing over the lip 23 and beneath the presser foot and needle. The braid or that part being sewed to the 20 already formed part of the hat is passed under the guide rod 9 with one edge bearing against the guide flange of the gage 6, and the other edge of the braid passing beneath the edge of the gage G and under the edge 25 of the hat so that the needle will stitch through both the formed portion of the hat and braid. By providing the gage with the lip 23 and curving the foot up as shown the proper feeding of the formed portion of the 30 hat below the presser foot is assured, the pressure of the spring 20 on the presser foot will always maintain the hat and braid in firm engagement assuring a tight stitch, the said foot readily giving or moving up to 35 compensate for any unevenness in the thickness of the braid but still maintain the hat and braid in firm engagement and in no way interfering with the proper feeding thereof as the machine is operated.
40. It will be observed that by rotating the adjusting stud 10 the gage 6 may be readily moved toward or away from the stitch plate for different widths of braid, and that the

gage G may be adjusted by the screw 26 toward and away from the stitch line or 45 needle position to regulate the distance of the stitch from the edge of the hat.

Variations may be resorted to within the scope of my invention.

Having thus described my invention, I 50 claim:

1. In a straw hat sewing machine, the combination with the presser-bar, of a presser-foot having a shank portion whereby it is detachably secured to the presser-bar, and the foot pivotally connected to the shank at the rear end; a spring to normally force the foot downward away from the shank; a guide pin carried by the foot to slidably engage in an aperture in the bottom of the shank to prevent sidewise movement of the foot; and a guide adjustably carried by the shank of the foot.

2. In a straw hat sewing machine, the combination with the presser-bar, of a 65 presser-foot having a shank whereby it is detachably secured to the presser bar, the foot portion pivotally connected to the shank at the rear end and curved upwardly at the forward free end; a spring to normally 70 force the foot downward away from the shank; a guide pin carried by the foot to slidably engage in an aperture in the shank to prevent sidewise movement of the foot; and a gage adjustably carried by the shank 75 of the foot, said gage extending beyond the forward end of the foot and provided with a laterally projecting lip located in a plane below the foot and curved reversely to the curvature of the foot, substantially as and 80 for the purpose specified.

WILHELM JASPER
